Primary Examiner — Jonathan J Han*Assistant Examiner* — Molly K. Orzechowski(74) *Attorney, Agent, or Firm* — Olive Law Group, PLLC**CLAIM**

The ornamental design for a sandal, as shown and described.

DESCRIPTION

FIG. 1 is a top, front, right side perspective view of a sandal, showing my new design;

FIG. 2 is a bottom, rear, right side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion “9” in FIG. 1.

The broken lines illustrate the portions of the sandal and form no part of the claimed design. The dot-dash-dot broken lines define the boundaries of the enlarged view and form no part of the claimed design.
